UNITED STATES PATENT OFFICE.

CHARLES H. NOWACK, OF CHICAGO, ILLINOIS, ASSIGNOR TO AMERICAN CAN COMPANY, OF NEW YORK, N. Y., A CORPORATION OF NEW JERSEY.

MEASURING CAN.

Application filed February 8, 1918. Serial No. 215,947.

To all whom it may concern:

Be it known that I, CHARLES H. NOWACK, a subject of the Emperor of Austria-Hungary, residing in Chicago, in the county of Cook and State of Illinois, have invented a new and useful Improvement in Measuring Cans, of which the following is a specification.

This invention relates to dispensing containers and more particularly to containers carrying finely comminuted material, such as pulverized coffee, coffee substitutes, sugar and other powdered or granulated substances, and has for its object broadly the provision of a container from which may be delivered desired, predetermined, uniform quantities—as, for example, in the case of a container of this character provided for coffee or coffee substitute, sufficient material to make one, two or more cups, as may be desired.

The object of the invention is the provision of a container of this character consisting of few cheaply provided and accurately working parts.

Another object of the invention is the provision of a container of this character, which, by reason of the measuring device, will require little or no additional space, or obstruct in an appreciable degree the interior.

Other objects and advantages of the invention will be apparent as it is better understood from the following description when considered in connection with the accompanying drawing illustrating a preferred embodiment thereof.

Referring to the drawing:

Figure 1 is a vertical section taken through a container embodying my present invention;

Fig. 2 is a section taken substantially on the line 2—2 of Fig. 1;

Fig. 3 is a bottom plan view of the same;

Fig. 4 is an enlarged portion of the section shown in Fig. 1.

The container embodying my present invention comprises a body 11 of any suitable form and construction having secured to it at the top an annular partial closure 12, in which may be frictionally seated or otherwise secured a cap or closure 13. The bottom closure 14 is seamed to the side of

the body and upon this is mounted a dispenser or measuring cap 15. This seam forms a projection or flange within which the measurer is located (Fig. 1), this flange forming no part of the mounting for the rotary element but extending below the latter so as to make the bottom of the can even when it is set down and preventing the measurer from striking against a table and protecting it from being bent out of shape. A circular part of the bottom indicated at 16 is set off by drawing inwardly the material to provide a wall 17 extending part way around the dispenser 15 and having a height at the point of greatest drawing equal to the height of the dispenser and tapering to almost nothing at the diametrically opposite side.

The dispenser consists of a disk having a peripheral flange 18 and a central depressed part 19 contacting with an upwardly extending portion 21 at the geometrical center of the drawn part of the closure, registering openings 22 being provided for receiving a pivot 23. The flange 18 and the wall 17 at its highest point are provided with registering openings 24 and 25, which permit the material of the container to enter the dispenser. The opening 24 in the flange 18 of the dispenser is preferably formed by slitting the material and bending the set-off part up and over into a lip or finger piece 26, which may be engaged to turn the dispenser from the receiving position shown in Figure 1 to the dispensing position shown in Fig. 2, in the course of which movement the opening 24 is first moved out of registration with the opening 25, closing the container, and then around until it passes the confining wall 17 and into pouring position. It will thus be manifest that the dispenser is provided with a single pivotally mounted flanged disk or cup, and the size of the dispenser may be so regulated in the construction of the container as to provide the delivery of a unit amount of material—in the case, for example, of coffee substitutes, the amount necessary to be placed in a cup of water to constitute a cup of cereal coffee.

It is thought that the invention and many of its attendant advantages will be better understood from the foregoing description and it will be apparent that various changes may be made in the form, construction and

arrangement of the parts without departing from the spirit and scope of the invention or sacrificing all of its material advantages, the form hereinbefore described being merely a preferred embodiment thereof.

It will be observed that the material enters and leaves the measuring device by restricted openings, which has the effect to spread out or distribute the material which is ordinarily of more or less powdered nature, and in entering the measuring device through the restricted openings 25 and 24, and in leaving the measuring device through the same opening 24 any cakes of the material are more or less broken up and disintegrated, which is of advantage in the dispensing and sprinkling of the material.

I claim:

1. A dispensing container having mounted on one of its walls a rotatable hollow cap turning in a plane nearly parallel with said wall, so that one side of the cap is within the container and the opposite side is exterior to the container, said cap having an opening through its peripheral wall into its interior and said container having an interior wall surrounding said cap and provided with an opening whereby the cap may be supplied with material from the container, and said wall may cut off the interior of the container from the interior of the cap when the latter is turned to place its interior in communication with the exterior of the container for dispensing material from within the cap.

2. A dispensing container for comminuted material, comprising a closure, a measuring cap pivotally mounted on said closure, said closure being depressed to provide a wall part way around said measuring cap and a bottom which lies in a plane at a right angle to the axis of the cap, and said closure and cap being provided with registering openings, the opening in said closure being in said wall, and the opening in said cap adapted to register therewith for filling and to be positioned beyond said wall for dispensing, the measuring cap having an axis of turning which is inclined towards the side of the container.

3. A measuring can having a portion of its end set off inwardly to form a seat, the bottom of which is at an angle to said end, said seat communicating with the interior of the can and open to the exterior of the can, a measuring cup fitting in said seat and rotary therein and having an opening adapted to be registered with the interior of the can and then with the exterior thereof, and means for retaining said measuring cap in said seat.

4. A measuring can having a portion of its end set off inwardly to form a seat the bottom of which is at an angle to said end and communicating with the interior of the

can and having an outlet therefrom to the exterior of the can, a measuring cap fitting in said seat and rotary therein and having an opening adapted to be registered with the interior of the can and then with said outlet, and means for retaining said measuring cap in said seat.

5. A measuring can having a portion of one of its walls set off inwardly to form a seat communicating with the interior of the can and having an outlet therefrom to the exterior of the can, a measuring cap fitting in said seat and rotary therein in a plane substantially parallel with a part of said wall and having an opening adapted to be registered with the interior of the can, and means for retaining said measuring cap in said seat, said measuring cap being adapted to dispense its measured contents when its said opening is turned away from said inlet.

6. A can end adapted to be secured to a can body to form a measuring can, said can end being formed with an inclined seat set off inwardly and having an inlet opening, and combined therewith a rotary measuring cap fitting in said seat and having an opening adapted to be registered with said inlet opening and forming a dispensing outlet when the cap has been properly positioned by rotation, and means for retaining the cap in said seat.

7. A dispensing container having a measurer of sheet metal and of hollow cylindrical shape and formed with a peripheral wall having a dispensing aperture and formed with an outer end wall, said measurer being applied endwise against a wall of said container, said container having a portion which is curved to fit the periphery of the measurer and which is formed with a filling aperture with which the aperture of the measurer may register, and means pivotally connecting the measurer with the container.

8. A dispensing container having a measurer of sheet metal of cylindrical cup-shape and formed with a peripheral wall having a dispensing aperture and with an outer end wall, said measurer being applied with its open face against a portion of a wall of said container, said container having a portion which is curved to correspond with the periphery of the measurer and which is formed with a filling aperture with which the aperture of the measurer may register, and means pivotally connecting said measurer with the container.

9. The combination of a container, and a rotary measurer and dispenser mounted on the bottom wall of the container and having an axis the direction of which is across said wall, said measurer having a communication to the interior of the container and a cut-off from the exterior when it is turned to receiving position and having a communication to the exterior of the container and a

cut-off from the interior when it is turned to dispensing position, the container having a projecting flange which surrounds said measurer at a distance from the same, and the measurer projecting outwards from the wall of the container within said flange and to a less distance than the latter, whereby the container may be supported evenly on a

table or the like with the measurer out of contact with the support.
